poration of California

Application April 30, 1945, Serial No. 591,209

14 Claims. (Cl. 137—144)

1

This invention relates to an electro-magnetic reset valve for fluid fuels.

Such valves are used in fuel supply systems to optionally control the flow of fuel to the main burner, and to prevent such flow of fuel unless a pilot flame is burning. As long as the pilot flame is burning, the valve may be opened and closed as desired, the pilot flame serving to ignite the fuel passing to the burner whenever the valve is open. Upon failure of the pilot flame, passage of fuel through the valve is prevented, and can not be reestablished until the pilot is lighted.

It is an object of this invention to provide a reset valve structure, wherein a single valve serves as both the safety valve and the control valve.

It is another object of this invention to provide a valve structure wherein a single electro-magnet serves to control a pair of valves.

It is another object of this invention to provide a valve structure wherein a single electro-magnet serves to operate a pair of valves in response to energization and deenergization of the magnet, the electro-magnet itself being movable for supplementarily operating one of said valves.

It is another object of this invention to provide a reset valve having a closure member optionally operable to control the passage of fuel through the valve, and arranged to close automatically in response to the creation of an unsafe condition.

It is another object of this invention to provide a reset valve having a closure member optionally operable to control the passage of fuel through the valve during energization of an electro-magnet, and which closes automatically upon deenergization thereof.

This invention possesses many other advantages, and has other objects which may be made more clearly apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

In the drawings:

Figure 1 is a longitudinal section through a valve incorporating the invention;

Figure 2 is a cross section taken as indicated by the line 2—2 on Figure 1;

2

Figure 3 is a fragmentary transverse section taken as indicated by the line 3—3 on Figure 1, but showing a different operating position of the parts; and

Figures 4 and 5 are views similar to Figure 3, showing other operating positions of the parts.

This valve is of the type for controlling the fluid fuel supply to a burner which is operated at irregular intervals, a constantly burning pilot flame being provided for igniting the main burner after periods of inactivity.

The valve structure comprises a main closure member 1 which is arranged to be manually operable for optionally controlling the supply of fuel to a main burner (not shown). Obviously, it is important to provide means whereby, upon extinction of the main burner and of the pilot burner, the supply of fuel to these burners is interrupted. Further, means must be provided for preventing reestablishment of the supply to the main burner until the pilot burner has been re-lighted. For this purpose, the main closure member 1 controlling the flow of fuel through the valve is of magnetic material and is arranged to be movable to open position through the medium of an electro-magnet 2, energized in response to electricity generated by the heat of the pilot burner flame in a well known manner, as by a thermocouple (not shown). The magnet 2 is arranged to be moved by the control handle 3, whereby, when the pilot flame is burning and the magnet 2 is energized, the closure 1 may be moved by moving the magnet, optionally to control the passage of fuel through the valve or to prevent it entirely. Upon extinction of the pilot burner the electro-magnet 2 is deenergized and loses control of the closure member 1. Thus, if the closure 1 was in open position, it would immediately close, stopping all flow of fuel. Further, it would be impossible to move closure 1 to open the valve until the magnet 2 was again energized, thus ensuring against opening of the valve until the pilot burner is lighted. To permit control of the closure 1 only in response to movement of the magnet 2, the magnet is so proportioned and arranged as to be incapable of influencing the closure 1 unless the magnet 2 is moved to initially engage the closure. A supplemental or by-pass valve 4 is provided for supplying fuel

to the pilot burner when the main valve is closed, and is arranged to be maintained in open position only as long as the magnet 2 is energized. In this way, escape of unignited fuel from the pilot burner is prevented.

When it is desired to light the pilot burner,

the magnet 2 is moved downwardly by means of the handle 3, to engage the main valve closure 1. A thumb button 6 is arranged to open the bypass valve 4, by appropriate operation after the magnet 2 has been moved into engagement with the closure 1. Hence, the supply of fuel to the pilot burner may be established and the burner lighted when desired. After a brief interval the magnet 2 becomes energized so that the closure 1 will be lifted with the magnet 2 to open the valve when the magnet is moved upwardly by the handle. By appropriate operation of the handle 3 to raise and lower the magnet 2, the closure 1 may be moved to fully open position or to closed position, or to any intermediate position to optionally control the passage of fuel. Upon flame failure and deenergization of the magnet 2, the closure 1 immediately moves to closed position.

Referring to Figures 1 and 2, the valve structure is shown as comprising an elongated body 10 having oppositely directed threaded openings 11 and 12 for connection to suitable conduits and forming, respectively, the inlet and the outlet. A wall 13 separates the inlet 11 from the outlet 12 and is provided with a port 14 surrounded by an annular valve seat 15 for permitting passage of fuel through the body 10. The main valve closure 1 is adapted to close port 14 by engagement with seat 15, and is movable axially away therefrom to open the port 14, hence the amount of fuel passing through the port being determined by the distance of the closure 1 from its seat 15.

The body 10 is provided with an upwardly directed cylindrical extension 16 above the port 14, closed at its upper end by a detachable cover 17 and providing a space 18 in continuous communication with the inlet 11 through space 19.

The magnet structure 2 is supported in the space 18 for movement axially of the seat 15 and comprises a pair of spaced concentric tubular members 20 and 21 of magnetic material secured in assembled relationship by rings 22 and 23 of non-magnetic material and providing a space for accommodating a winding 24. A cap 27, also of non-magnetic material, is secured to the upper end of the outer shell 20 and has a central spherical socket 28 rotatably engaging a ball 29 formed in the lower end of the valve stem 30.

The valve stem 30 has an enlarged exteriorly threaded intermediate portion 31 which is in engagement with an interiorly threaded boss 32 formed on the cover 17. The valve stem 30 also has a reduced cylindrical upper portion 33 projecting above the boss 32, with the handle 3 secured thereon, suitable packing means indicated by 34 being provided to prevent leakage past the stem 30.

Rotation of the stem 30, as by means of the handle 3 serves to move the magnet 2 either toward or away from the valve seat 15, depending on the direction of rotation, and if the magnet 2 is energized by current passing through the winding 24, the closure member 1, after initial movement of the magnet 2 into engagement with the closure will be correspondingly moved, to open and close the port 14. Upon deenergization of the magnet 2, by interruption of the current flow in the winding 24, the closure 1 will drop to seat 15 by gravity and close the port 14.

To maintain the electro-magnet 2 and the closure 1 in substantial axial alignment with the seat 15 at all times, the magnet 2 and the closure 1 are made of the same outside diameter and are

guided by several vertically extending ribs 35 on the interior of the body extension 16. Furthermore, to prevent rotation of the stem 30 being imparted to the magnet 2, the latter is restrained by a pair of lugs 36 formed on the exterior of the shell 20 and engaging opposite sides of one of the ribs 35.

To provide a safety feature by insuring that such closure occurs upon the establishment of an unsafe condition, the energization of the magnet 2 is made dependent in a known way upon the existence of the pilot flame. Thus leads 37 and 38 from the coil 24 are connected to binding posts 39 and 40 in the wall of the extension 16 and these in turn are connected by leads (not shown) to a thermocouple subjected to the heat of the pilot flame. Upon flame failure, the supply of current is substantially instantaneously interrupted, the magnet 2 is deenergized, allowing closure 1 to drop to closed position, and preventing movement thereof to open position until such time as the pilot flame is again burning.

To insure against escape of unignited fuel at the pilot burner, the closure 1 is arranged to interrupt the supply of fuel to the pilot burner at the same time as it closes the port 14. For this purpose, a second valve seat 43 is provided and is so arranged that the closure 1 seats thereon and on seat 15 simultaneously. The seat 43 may conveniently surround the seat 15 and be spaced therefrom to provide an annular cavity 44, into which opens a supplemental outlet port 45, connected with the pilot burner (not shown) by a conduit 46 (see Figure 3). When the closure 1 is unseated fuel can pass freely from the inlet 11 into the space 44 and thence to port 45 and the pilot burner. When the closure 1 is seated, such passage is interrupted.

However, it is necessary to permit fuel to flow to the pilot burner when the closure 1 has been operated to seat to extinguish the main burner intentionally, and also to establish fuel flow to the pilot burner to initiate operation of the system or to restore operation after flame failure. For this purpose, a by-pass or supplemental valve 4 is provided.

Thus, the valve closure 1 is in the form of a hollow disc as disclosed in my copending application, Serial No. 547,383, filed on July 31, 1944, comprising a lower member 49 with a raised peripheral lip 50 to which the upper member 51 is secured as by screws 52. The upper and lower members 49 and 51 cooperate to form a chamber of space 53 which, when the closure member 1 is seated, is in continuous communication with the space 44 between the valve seats 15 and 43 by one or more ports 54 through the lower member 49.

The upper member 51 has a central port or opening 55 providing a valve seat 56 and adapted to be controlled by a closure member 57, which may be conveniently a steel ball. The upper face of the member 51 is provided with a number of radially extending grooves 58, for maintaining the port 55 in free communication with the space 18 when the closure 1 is engaged by the magnet structure 2. A light compression spring 60 seated in a well 61 on the lower member 49 serves to urge the closure 57 toward its seat. With the closure 1 seated, fuel can pass freely to the pilot burner if the supplemental closure 57 is unseated, via grooves 58, port 55, space 53, ports 54 and cavity 44; if the closure 1 is unseated fuel can pass to the pilot burner as well as to the main burner directly via cavity 44; if both closures 1 and 57 are seated no fuel at all can pass.

Means are provided whereby the magnet 2 when energized serves to maintain the supplemental closure 57 unseated, thus permitting fuel to flow to the pilot regardless of whether the closure 1 is seated or not. For this purpose an armature 65 is provided above the magnet 2 having a push rod 66 extending downwardly through the inner tubular member 21 of the magnet. The push rod 66 is of such length as to maintain the closure 57 unseated when the closure 1 and the armature 65 are in contact with the opposite faces of the magnet 2 (see Figure 1). The magnet 2 may be provided with pole pieces 64 which cooperate with the armature 65 to reduce the reluctance of the magnetic circuit between the armature and the magnet.

The armature and push rod 65 and 66 are guided for movement substantially axially of the magnet 2 and the closure 1 by a number of lugs 67 near the lower end of the inside of tube 21 and by the pins 68. These pins 68 have heads 69 to limit upward movement of the armature 65 and push rod 66 by a light compression spring 70 confined between the armature 65 and lugs 67, when the magnet 2 is deenergized. As long as the magnet 2 is energized, the supplemental closure 57 is maintained unseated as shown in Figures 1 and 3. When the magnet is deenergized, the armature 65 is moved up to engage heads 69 by the spring 70, the closure 57 thus being seated by the spring 60, as shown in Figures 4 and 5.

The magnet 2 is incapable when energized of moving the armature 65 to a position where it unseats the closure 57. To unseat the closure 57 and open the by-pass, a rod 72 slidable in an axially extending bore 73 of the valve stem 30 is provided. The rod 72 has an enlarged upper portion 74 carrying the thumb button 6 and accommodated in an enlarged portion 75 of the bore 73. The bore 73 and its enlarged portion 75 provide an upwardly directed shoulder 76, while the enlarged portion 74 of the rod 72 provides a downwardly directed shoulder 77. A light impression spring 78 confined between the shoulders 76 and 77 serves to urge the rod 72 upwardly and to maintain resiliently the head 79 at the lower end of the rod 72 against the lower end of the stem 30. Suitable packing 80 is provided between one of the shoulders, as 76, and the adjacent end of the spring 78 to prevent leakage past the stem.

The arrangement is such that with the parts in the relative positions shown in Figure 5, downward movement of the rod 72 as by pressure on thumb button 6, will first cause the head 79 to engage the armature 65, and the push rod 66 to engage the closure 57, and then cause the armature 65 to move into contact with the upper face of the magnet 2, and cause the closure 57 to move to open position. Upon release of the pressure, if the magnet 2 has become energized, as by the pilot flame, the armature 65 and the closure 57 will remain in these positions, rod 72 returning to its initial position. If, however, the pilot flame is not burning all parts will return to their initial positions, closure 57 reseating.

The operation of the valve may now be discussed. With the magnet 2 in engagement with the closure 1, and the pilot flame burning and magnet 2 energized, the by-pass closure 57 will be maintained in open position. By appropriate rotation of the handle 3 to raise and lower the magnet 2, the closure 1 may be moved to the fully open position of Fig. 3, or to some intermediate

position and/or returned to closed position as desired.

Upon flame failure, the magnet 2 is de-energized, allowing the closure 1 to seat by gravity. Also, the armature 65 is released, ensuring closing of the by-pass 4. The parts are then in the relative positions of Fig. 4. If failure of the pilot flame occurs while the closure 1 is seated, armature 65 is released as before, allowing the closure 57 to seat, as shown in Fig. 5. In both cases, all passage of fuel through the valve is stopped. If an attempt is made to open the valve when the pilot flame is not burning, the magnet 2, as it moves upward, leaves the closure 1 seated, as shown in Fig. 4, maintaining the valve closed. It is impossible to unseat the closure 1 unless the pilot flame is burning.

The inventor claims:

1. A reset valve for fluid fuels having a main flow passage therethrough, a main valve closure for controlling flow of fuel through the valve and urged to closed position, a movable electro-magnet, including a movable coil, movable into engagement with said main valve closure to enable said electromagnet coil, when energized, to move said closure optionally between open and closed positions in response to movement of the magnet, and when deenergized releasing said closure for movement to closed position, means adapted to form a supplemental flow passage for passing fuel when said main closure is in closed position, a supplemental closure for said supplemental flow passage, and means controlled by said magnet when energized, for maintaining said supplemental closure in open position.

2. A reset valve for fluid fuels comprising, a body having an inlet, a main outlet, and a supplemental outlet, means forming a ported seat for passing fluid through the valve to said main outlet and to said supplemental outlet, a main closure member movable with respect to said seat for controlling flow of fluid therethrough, an electro-magnet supported for movement toward and away from said seat, serving when energized and upon movement to initially engage said closure, to optionally move said closure between port opening and port closing positions in response to movement of the magnet, means for optionally passing fluid to said supplemental outlet when said closure is in port closing position, including a by-pass port, a supplemental closure for said by-pass port, means for operating said supplemental closure to open and to close, and means whereby said magnet upon energization acts to maintain the supplemental closure in open position.

3. A reset valve for fluid fuels comprising, a body having an inlet, a main outlet, and a supplemental outlet, a pair of valve seats for passing fluid respectively to said main and supplemental outlets, a main closure member cooperating with said seats, operable to close and open both of said outlets, means forming a by-pass for passing fuel to said supplemental outlet when the main closure is seated, a supplemental closure for the by-pass, operable to open to pass fuel to said supplemental outlet and to close, electro-magnetic means, including a movable coil, movable into engagement with said main closure member to enable said electro-magnetic means to shift said closure to open position when said electro-magnetic means is energized, and electro-magnetic means for maintaining said supplemental closure in fuel passing condition for all adjusted positions of the main closure member.

4. A reset valve for fluid fuels having a main flow passage therethrough, a main valve closure, an electro-magnet, including a movable coil, movable to cause, when energized, said main valve closure to move to open and to close in accordance with the movement of said electro-magnet, means forming a supplemental flow passage for passing fluid when said main valve closure is in closed position, a supplemental closure for cooperating with the main valve closure to control said supplemental flow passage, means urging said supplemental closure to closed position, and means cooperating with said electro-magnet, when the electro-magnet is energized, to maintain said supplemental closure in open position for all adjusted positions of the main valve closure.

5. A reset valve having a body with an inlet, a main port and a supplemental port for passing fluid fuel through the valve, a pair of valve closure members for respectively controlling the passage of fuel through said ports and urged to port closing position, a movably mounted electro-magnet for moving, when energized, one of said closure members to open and to close its associated port in response to movement of the magnet, means movable independently of said electro-magnet to cause the other closure member to open the other port, and means whereby said magnet when energized maintains said other closure in port opening position.

6. A reset valve having a body with an inlet, a main port and a supplemental port communicable with said inlet for passing fluid fuel through the valve, a pair of closure members for respectively controlling passage of fuel through said ports and urged to port closing condition, means operable upon establishment of a safe condition for moving the main port closure member to open and close said main port, means whereby the means for moving said main port closure member is rendered ineffective to move said main port closure member to open position and is rendered ineffective to hold the main port closure member in open position upon establishment of an unsafe condition, means for causing passage of fuel through said supplemental port as long as said safe condition persists and for interrupting said passage upon establishment of an unsafe condition, and means for optimally causing passage of fuel through said supplemental port after establishment of an unsafe condition.

7. A reset valve having a body with an inlet, a main port and a supplemental port communicable with said inlet for passing fluid fuel through the valve, a pair of closure members for respectively controlling passage of fuel through said ports and urged to port closing position, means operable upon establishment of a safe condition for moving the main port closure member to open and close said port, means whereby the means for moving said closure is rendered ineffective to move said main port closure member to open position and is rendered ineffective to hold the main port closure member in open position upon establishment of an unsafe condition, means maintaining said other closure in open position as long as said safe condition persists, and operable upon movement of said main port closure to closed position in response to an unsafe condition to permit said other closure to close said supplemental port, and means for optionally moving said other closure to open position.

8. A reset valve for fluid fuels having a main

flow passage therethrough, a main valve closure for controlling flow of fuel through the valve, means forming a supplemental flow passage for passing fuel when the main closure is in closed position, a supplemental valve closure for said supplemental flow passage and urged to closed position, a movably mounted electro-magnet, said magnet being movable to a position to attract said main closure when said magnet is energized and thereafter to move said member to open and to close in response to movement of the magnet, means for moving said supplemental closure to open position, and means whereby said electro-magnet when energized maintains said supplemental closure in open position.

9. A reset valve for fluid fuels having a main flow passage therethrough, a main valve closure for controlling flow of fuel through the valve and urged to closed position, means forming a supplemental flow passage communicable with said main passage for passing fuel when the main closure is in closed position, a supplemental valve closure for said supplemental flow passage, means effective upon establishment of a safe condition to operate said main closure optionally to open and to close, and ineffective to hold the main closure in open position and ineffective to move said main closure to open position upon establishment of an unsafe condition, means urging said supplemental valve closure to closed position, means for moving said supplemental valve closure to open position to establish a safe condition, and means maintaining said supplemental closure in open position, as long as a safe condition persists.

10. A reset valve for fluid fuels comprising a body having an inlet, a main outlet, and a supplemental outlet, a pair of spaced valve seats, one within the other, in communication with the inlet, a passage establishing communication between the space within the inner seat and the main outlet, a passage establishing communication between the space between the seats and the supplemental outlet, a hollow closure member for cooperating with said seats to close said passage and having an inlet port for admitting fuel into said member as well as a passage for admitting fuel from the interior of the member to the space between the seats, valve means for controlling said inlet port and resiliently urged toward closed position, an electro-magnet supported for movement with respect to said seats and adapted upon movement toward the valve seats to engage the closure member, said closure member being arranged to be held for movement with said magnet, when said magnet is energized and engaging said member, whereby the position of said member is adjusted with respect to said seats by movement of said magnet, an element carried by said magnet and adapted for movement with respect thereto to enter said inlet port and unseat said valve means when said magnet and said closure member are in engagement, manually operable means for moving said element to unseat said valve means, and means whereby said magnet when energized maintains said element in valve opening position.

11. A reset valve for fluid fuels comprising a body having an inlet, a main outlet, and a supplemental outlet, a pair of spaced valve seats, one within the other, in communication with the inlet, a passage establishing communication between the space within the inner seat and the main outlet, a passage establishing communication between the space between the seats and the

supplemental outlet, a hollow closure member for cooperating with said seats to close said passages and having an inlet port for admitting fuel into said member as well as a passage for admitting fuel from the interior of the member to the space between the seats, valve means for controlling said inlet port and resiliently urged toward closed position, an electro-magnet supported for movement with respect to said seats and adapted upon movement toward the valve seats to engage the closure member, said closure member being arranged to be held for movement with said magnet when said magnet is energized and engaging said member, whereby the position of said member is adjusted with respect to said seats by movement of said magnet, an element extending through the magnet and movable with respect to the magnet to enter said inlet port and unseat said valve means when said magnet and said closure member are in engagement, manually operable means for moving said element to unseat said valve means, and an armature carried by said element adapted to engage the opposite face of the magnet from that engaged by said closure to maintain said valve means unseated when the magnet is energized and engaging said closure member.

12. A reset valve having a pair of ports for passing fluid fuel through the valve, closure members respectively for said ports and movable in opposite directions to close said ports, means urging said closures to port closing positions, and an electro-magnet, including a movable coil, movable into engagement with one of said closure members serving when energized to maintain 35 said closures in port opening condition.

13. A reset valve for fluid fuels having a main flow passage therethrough, a main valve closure for controlling flow of fuel through the valve and urged to closed position, a movable member including an electro-magnet which, when energized and engaging said closure causes said closure to move with said member, said member being movable between positions in which said closure opens and closes said flow passage respectively, 45 said magnet when deenergized releasing said closure for movement to closed position independ-

ently of said member, a first means adapted to form a supplemental flow passage for passing fuel when said closure is in closed position, a supplemental closure for said supplemental flow passage and urged to closed position, a second means carried by said movable member for optional movement with respect thereto for operating said supplemental closure to open position, said second means after movement of said main closure to closed position in response to release by said electro-magnet, being rendered effective to open said supplemental closure by movement of said member to cause said magnet to engage the closure, and means whereby said magnet when energized maintains said supplemental closure in open position.

14. A reset valve for fluid fuels having a main flow passage therethrough, a main valve closure for controlling the flow of fuel through the valve and urged to closed position, a movable electro-magnetic coil movable into engagement with said main valve closure to enable said electromagnet coil, when energized, to move said closure optionally between open and closed positions in response to movement of said coil, and de-energizable to release said closure for movement to closed position, means forming a supplemental flow passage for passing fuel when said main closure is in closed position; a supplemental closure for said supplemental flow passage, and means controlled by said electromagnetic coil, when energized, for maintaining said supplemental closure in open position.
